C. W. MORRIS

OIL WELL BAILER

Filed April 7, 1922

Patented July 10, 1923.

1,461,365

UNITED STATES PATENT OFFICE.

CHARLES WILLIAM MORRIS, OF LARAMIE, WYOMING.

OIL-WELL BAILER.

Application filed April 7, 1922. Serial No. 550,236.

To all whom it may concern:

Be it known that I, CHARLES W. MORRIS, a citizen of the United States, residing in the city of Laramie and State of Wyoming, have invented new and useful Improvements in Oil-Well Bailers, of which the following is a specification, reference being had to the accompanying drawings.

This invention is an oil well bailer, for removing mud, water, sand, gravel, rock and the like from the bottoms of oil wells in the process of drilling. The object of the invention is to provide a practical, efficient and readily operable device of this kind.

15 In the drawings:

Figure 1 is an elevation of the bailer, sections being broken out to show the interior mechanism. The bailer is here shown resting on the derrick floor preparatory to being 20 "set" and lowered in the well.

Figure 2 is a similar view, showing the bailer properly "set" for lowering.

Figure 3 is a similar view, showing the bailer being lifted out of the well, after 25 loading.

The invention comprises a hollow, cylindrical body or barrel 1, slightly reduced at the lower part 2 to facilitate the lowering of same into the well or tubing without catching or tripping, and being closed at the top 30 end 14. At the lower end of this barrel are hinged at 3 two oppositely disposed, scoop-jaws 4, suitably sharpened on their edges 5. These jaws are semi-circular in cross section 35 so when opened out and down they will conform to the curved sides of the barrel and in effect form a sort of extension thereof for receiving the material to be bailed out. The jaws 4 are also proportioned so as to close 40 together nicely on a central line 6, as shown in Figure 3. The jaws 4 have rigidly connected shanks 7 which set inwardly at approximate right angles to the body of the jaws, and connecting rods 8 are pivoted at 9 to the ends of these shanks. The upper ends 45 of the rods 8 are pivoted at 10 to a plate 11. A square draw-rod 12 passes freely through the plate 11 and has a nut 13 secured to the lower end thereof. The draw rod 12 passes 50 freely through the top end 14, and ends in an eye 15 to which the line 16 is attached. Spaced stops 17 and 18 are mounted on the rod 12, one above and one below the top 55 closure 14, so as to allow a certain play up and down to said rod 12. Two hook arms 19 and 20 are pivoted at 21 to opposite sides

of the rod 12 and have hooks 22 and 23 adapted to swing out and engage cross bars 24 and 25 mounted across the cylinder 1 on opposite sides. Chains 26 and 27 are attached at 28 and 29 to the arms 19 and 20 and extend freely through the top closure 14, ending in rings 30 and 31. These chains afford means for pulling the hooks 22 and 23 out into engagement with the bars 24 and 25.

In use, the apparatus is rested upon the derrick floor, the jaws 4 being closed. The hooks 22 and 23 are pulled out under the bars 24 and 25. By pulling the line 16 taut 70 the weight of the entire apparatus is then suspended from the hooks 22 and 23, and the jaws 4 fall open by their own weight. The device is thus lowered to the bottom of the well, where the material to be bailed out 75 passes up through the open jaws into the barrel. As the bailer strikes bottom, the draw rod 12 drops down until the stop 17 rests upon the plate 11, and the hooks 22, 23 fall away from the bars 24, 25. As the line 80 16 is drawn upon, the nut 13 engages the under side of the plate 11, thus pulling upon connecting rods 8 and closing the jaws 4. The bailer is then pulled out of the well and emptied and the operation repeated, as desired.

While I have herein described a certain, specific method of constructing and assembling the elements of my invention, it is understood same may be varied in minor details, not departing from the spirit of my invention as defined in the appended claims.

I claim:

1. A well bailer, comprising a hollow cylinder open at bottom and closed at top; 95 scoop shaped jaws hinged at the lower end and adapted to open in conformity with the contour of the cylinder and to close together on a central line; shanks rigidly secured to the jaws and extended inwardly; connecting rods pivoted at their lower ends to said shanks; a plate secured to the upper ends of said connecting rods; a square draw rod passing freely through the said plate and freely through the top of the cylinder, and ending in an eye adapted to engage a line; stops on the draw rod above and below the cylinder top; cross bars oppositely mounted inside the cylinder; hook-arms oppositely pivoted to the draw rod, and carrying hooks adapted to swing out and engage the cross bars; and chains attached to the hook arms 100 105 110

and extended freely up through the top of the cylinder.

2. A well bailer, comprising a barrel open at bottom; jaws hinged at the bottom end to open and close centrally, said jaws having inwardly directed shanks set at an angle to the jaws; connecting rods hinged to the jaws; a draw rod slidingly engaging said connecting rods and freely passing through

the top of the barrel; cross bars inside the barrel; and hooks pivoted to the draw rod and adapted to swing out into engagement with the cross bars. 10

CHARLES WILLIAM MORRIS.
